UNITED STATES PATENT OFFICE

RUSSELL S. BEGG, OF DETROIT, MICHIGAN, ASSIGNOR TO BUDD WHEEL COMPANY, OF PHILADELPHIA, PENNSYLVANIA, A CORPORATION OF PENNSYLVANIA

DESIGN FOR A COMBINED DISK WHEEL AND HUB CAP

Application filed January 26, 1929. Serial No. 29,789. Term of patent 14 years.

To all whom it may concern:

Be it known that I, RUSSELL S. BEGG, a citizen of the United States, residing at Detroit, county of Wayne, State of Michigan, have invented a certain new, original, and ornamental Design for a Combined Disk Wheel and Hub Cap, of which the following is a specification, reference being had to the accompanying drawings, forming part thereof, wherein—

Fig. 1 is a perspective view of a combined

disk wheel and hub cap, showing my new design, and

Fig. 2 is an axial section through the combined disk and hub cap.

I claim:

The ornamental design for a combined disk wheel and hub cap, as shown.

Signed at Detroit, county of Wayne, State of Michigan, this 25th day of January, 1929.

RUSSELL S. BEGG.
